UNITED STATES PATENT OFFICE.

GEORGE H. JENNINGS, OF BROCKTON, MASSACHUSETTS.

SYSTEM OF HEATING.

SPECIFICATION forming part of Letters Patent No. 725,717, dated April 21, 1903.

Application filed February 14, 1901. Serial No. 47,343. (No model.)

To all whom it may concern:

Be it known that I, GEORGE H. JENNINGS, a citizen of the United States, residing in Brockton, in the county of Plymouth and 5 State of Massachusetts, have invented an Improvement in Systems of Heating, of which the following description, in connection with the accompanying drawing, is a specification, like characters on the drawing representing 10 like parts.

This invention relates to a system for heating by means of live or exhaust steam, which is particularly adapted for use in factories, mills, and like places.

15 The invention has for its object to provide a system with which a maximum heating effect may be obtained at a minimum cost. For this purpose I employ a circuit having its return for water of condensation connected 20 with a pressure-pump, and with said return is connected the cold-water-supply pipe, which is preferably provided with a spraying device, the cold water admixing with the warm water of condensation creating a vacuum in 25 the return side of the system, the amount of the vacuum varying with the amount of circulation and the temperature of the building being heated. The temperature of the cold 30 water is raised by the heat in the water of condensation, and its temperature may be raised still further by causing it to pass through a feed-water heater before entering the boiler. The feed-water heater may be of any suitable construction and is heated by 35 the exhaust-steam from the engine. The pump is provided on its discharge side with a vent-pipe communicating with the atmosphere and through which pipe any air in the system may be discharged into the atmosphere. 40 The supply side of the system may be connected with the exhaust or with the boiler and preferably with both, whereby exhaust or live steam may be used in the heating system. These and other features of this invention 45 will be pointed out in the claims at the end of this specification.

The drawing is a diagrammatic view of a heating system embodying this invention.

Referring to the drawing, *a* represents a 50 steam-boiler; *b*, an engine which is supplied with steam from the boiler *a* through the pipe *c*, the exhaust from the engine passing through

a pipe *d* to a cylinder or casing *e*, forming a feed-water heater. The heater *e* has an outlet-pipe *f*, which may communicate with the 55 atmosphere, and the outlet-pipe *f* has connected to it the supply side of the heating system—namely, the pipe *g*—which extends around the building or other structure to the various rooms to be heated, where it is suitably connected with heaters *h*, which are shown as radiators, but which heaters may be of any desired form or construction. In the present instance I have shown three radiators *h*, which may be located in the same 60 or different rooms of the building, each radiator having its inlet-pipe *j* connected to the main supply-pipe *g* and provided with a shut-off or valve *k*. The outlet-pipes *l* of the radiators are connected to a common return-pipe 70 *m*, which may and preferably will be provided with an enlargement or coupling *n*, with which the outlet-pipes for the radiators are connected. The return-pipe *m* is connected with the water-inlet port of a pressure-pump *o* of any 75 usual or suitable construction, having its water outlet or discharge-port connected by a pipe *p* with a coil *q* within the heater *e*, the said coil being connected by the pipe *r* with the boiler *a*. The return-pipe *m* in accordance 80 with this invention has connected to it the cold-water-supply pipe *s* for the boiler, and the said cold-water-supply pipe may and preferably will be connected with the coupling or enlargement *n*, which may be designated the “condenser.” The pipe *s* may and 85 preferably will be provided with a valve *u* and with a nozzle or spraying device *t* of any suitable construction, which is indicated by dotted lines in the drawing and by which 90 the cold water is distributed and more thoroughly commingled with the steam and water of condensation in the return-pipe. The cold water condenses the steam and forms a 95 vacuum on the return side of the heating system, which facilitates the circulation of the steam through the radiators or heaters *h*, and at the same time the temperature of the cold water is raised. The pressure-pump 100 draws the water of condensation through the return-main *m* and forces it through the feed-water heater back into the boiler. The water on its passage through the feed-water heater has its temperature still further raised

proximately to the boiling-point, so the boiler is supplied with water apparently at the temperature of steam. The gases in the system are taken care of by the pressure-pump and may be discharged through the pipe 2 to the atmosphere. The system is free of air, the valve 3, pipe 2 is nearly closed.

In the system just described it will be that the exhaust-steam from the engine is returned to the boiler by the pressure-pump in the form of water of condensation, condensation being effected by the spray of cold water admitted into the return-pipe. If it is desired to heat the building with steam, the pipe 4 is connected with the valve 5 which is effected, as shown, by the

shut-off valve

tem at a minimum expense, inasmuch as the usual feed-water pump is utilized for maintaining the vacuum and a separate vacuum-pump and hot-well are dispensed with.

The valve 6 in practice will preferably be open continuously, so as to admit a substantially small quantity of water sufficient to supply the boiler.

I prefer to effect the condensation of the steam in the return side of the system by admitting the cold-water supply for the boiler into the return-pipe 7; but I do not desire to limit my invention in this respect, as other forms of condensers may be used and the feed-water supplied to the boiler in any other desired manner.

I have for convenience of illustration represented the heater in the form of a radiator; but I do not desire to limit myself to any particular form of heater or to any particular

100 75 80 85 90 95 100

100 75 80 85 90 95 100

100 75 80 85 90 95 100

100 75 80 85 90 95 100

100 75 80 85 90 95 100

- turn-pipe intermediate of said heater and pressure-pump, and a boiler, a feed-water heater connected with said boiler and with the outlet-port of said pressure-pump, and a 5 vent-pipe connected to the discharge side of said pressure-pump, substantially as described.
5. In a system of the class described, the combination with a steam-supply pipe, of a 10 plurality of heaters connected therewith and provided with outlet-pipes, of a condenser into which the said outlet-pipes discharge, a cold-water-supply pipe communicating with said condenser, a common return-pipe connected with said condenser, a pressure-pump 15 with which said return-pipe is connected, a boiler with which said pressure-pump is connected, a vent-pipe communicating with the discharge side of said pump, and a valve in 20 said vent-pipe, substantially as described.
6. In a system of the class described, in combination, a boiler, a steam-supply pipe communicating therewith, a plurality of heaters connected with said supply-pipe and 25 provided with outlet-pipes, a condenser into which the said outlet-pipes separately discharge, a cold-water-supply pipe connected with said condenser and provided with a spraying device, a return-pipe connected with 30 the bottom of said condenser, a feed-water or pressure pump with which the said return-pipe is connected, an outlet-pipe for said pump connected with the said boiler, and a 35 vent-pipe communicating with the discharge side of the pump, substantially as described. 40
7. In a system of the class described, the combination with a steam-generator, radiators supplied therefrom, a return-pipe in free communication with said radiators, said return-pipe being closed to the atmosphere and 45 provided with a condensing means, a pump having its inlet in communication with said return-pipe, a pipe providing communication between the discharge-port of said pump and the steam-generator, and an air-vent located on the discharge side of said pump, substantially as described.
8. In a system of the class described, the combination with a boiler, of a heater connected therewith for the passage of steam 50 through it, a pressure-pump, a return-pipe for the heater connected with the inlet-port of said pressure-pump, means for connecting the discharge-port of the said pressure-pump with said boiler, and a pipe connected with 55 the discharge side of the pressure-pump and communicating with the atmosphere, to discharge the air accumulated in said pump into the atmosphere, substantially as described.
- In testimony whereof I have signed my 60 name to this specification in the presence of two subscribing witnesses.
